CRIB ATTACHMENT FOR BEDS

Paul C. Kelly, Rehoboth Beach, Del.

Application January 7, 1948, Serial No. 1,001

2 Claims. (Cl. 256—25)

1

This invention relates to children's cribs which may be readily erected from a collapsed condition to be conveniently and expeditiously mounted on a standard bed, couch, seat or similar article of furniture.

While cribs of this type have heretofore been proposed, nevertheless they are open to the objections that they are more or less tedious to manipulate; often require the aid of tools to effect final adjustment; frequently require separate hardware accessories for anchoring purposes which become lost or misplaced; do not provide adequate safeguard against injury to the infant or child; and, moreover, do not have adequate side wall rigidity for durability and strength.

Accordingly, a primary object of the invention is to provide a collapsible crib of maximum simplicity, eliminating the objections set forth, primarily because it consists of a plurality of side and end panels, the former including sections, all of which are permanently hinged together in such a way that at no time are there any free or loose ends to swing or to be brought together with fasteners, and presenting an ensemble which may be collapsed by relative movement first between the sections forming the side panels or long walls, and successively and progressively bringing the relatively short end panels in parallel relation to the then intermediate side panels to bring all of the walls and sections into nested parallel relation. When erecting the crib, the end panels are disposed toward the head and foot of the bed or the like, and the sections of the side panels are pulled apart to readily and quickly form the completed rectangular crib. Thus, by simple, effortless movement, the crib can be erected or collapsed.

Another object of the invention is to connect the several panels and sections by links which do not only provide the permanent connections heretofore mentioned, but also adequately compensate for the relative thickness of the sections when collapsed for storage or transportation, thereby enabling the permanently connected sections to be collapsed into a flat unit requiring a minimum of space and enabling the same to be conveniently fitted into a storage or transportation carton or case.

A further object is to provide means for rigidly holding the panels and sections in alignment upon erection for use so that the side walls cannot be accidentally collapsed. That is to say, certain of the rail portions of the sections of the side panels, as well as the end panels, are provided with slidable tubular locking means or latches

2

adapted to be shifted across the joint formed by the links to hold the contiguous related rails in alignment and, upon manual rotation engage the rods or posts connecting opposite top and bottom rails so that they cannot be accidentally shifted except by deliberate effort of the child's attendant.

A still further object is to provide simple means for attaching the crib to the bed or the like on top of the mattress or cushion, said means comprising buckles flexibly connected to the bottom rails of certain of the sections of the side panels and connected by a strip of webbing provided with a non-slipping coating so that when the crib is mounted on the bed or the like, it will not slide or shift on the covers.

With the above and other objects in view which will more readily appear as the nature of the invention is better understood, the same consists in the novel construction, combination and arrangement of parts, hereinafter more fully described, illustrated and claimed.

A preferred and practical embodiment of the invention is shown in the accompanying drawings, in which:

Figure 1 is a perspective view of the erected crib applied to a bed;

Figure 2 is a perspective view showing the crib in its initially collapsing position;

Figure 3 is a side elevation of the completely collapsed crib;

Figure 4 is a detail view of one of the links and its related latch sleeve as applied to opposite corners of the side and end panels;

Figure 5 is a detail perspective view showing the sliding latch sleeve for spanning the joint between the sections of the side panels to maintain them in latched or locked position;

Figure 6 is a detail perspective view showing the construction of Figure 5 when the side sections are collapsed;

Figure 7 is a detail perspective view of the crib collapsed in a carrying case or carton.

Similar reference characters designate corresponding parts throughout the several figures of the drawings.

As will be observed from the drawings, the present invention comprises opposite side panels A and B, and end panels C and D. The side panels A and B preferably include the sections 1, 2 and 3, 4, respectively, while the end panels are preferably in one piece. The sections of the side panels and the end panels themselves are dimensioned as to length so as to cooperate with hinge means in the form of pivoted links of dif-

ferent length for facilitating all of the sections collapsing into parallel relation as shown in Fig. 3. That is to say, the diagonally opposite sections 1 and 4 are short sections, whereas the sections 2 and 3 are long sections.

The panels A, B, C, D preferably comprise top and bottom rails 5 and 6 connected by the rods or posts 7.

The opposite corners B' and C' of the end panels and side panels are pivotally connected by links 8, while the opposite corners B² and C² are pivotally connected by the relatively longer members or spacing links 9 whose axes 9a are the collapsing hinges at the inner end of each link. Slidably mounted on the top and bottom rails 5 and 6 of the end panel C and D, there is provided a sleeve 10 (Fig. 4) having an open end bayonet slot 11. This sleeve may obviously have a continuous side slot with the angularly disposed notch at any selected location, as taught for example in Fig. 6. When the crib is collapsed, the sleeve 10 is moved backwardly onto its related rail 5 or 6 with the slot 11 being guided by one of the rods 7. On the other hand, when the crib is erected, as shown for example in Figure 1, the sleeve 10 is moved forwardly to span the link 9 as well as the related rail 6, thus preventing the link 9 from functioning and holding it in a locked rigid position as an extension of rail 6. When the sleeve 10 has been slidably moved over link 9, the said sleeve is then rotated outwardly through an appropriate angle to bring the angular end or notch 12 of the slot into engagement with the rod 7. Thus, the sleeve 10 will lock the link 9 against collapsing movement until the procedure just described is reversed by an authorized party to permit the collapsing of the crib.

The top and bottom rails of sections 1-2 and 3-4 are pivotally connected medially by the links 13. The top and bottom rails 5 and 6 of sections 2 and 4, for example, of the opposite side panels A and B, are provided with the sliding, tubular latches 14. These latches are preferably made in the form of a split sleeve forming a slot or channel 14a provided along one edge with a plurality of locking notches 15 (Figs. 5, 6). When the crib is erected, the sleeves 14 may be slidably moved along the related rail due to the slot 14a, thereby to be projected across the joint formed by the links 13. After the sleeve 14 has been moved across the joint, as shown in Fig. 5, the same may be angularly rotated outwardly so that the notches 15 engage with one or more of the rods 7 thereby locking bottom rails 5 and 6 of sections 2 and 4 joined by link 13 in a rigid position and preventing shifting movement of the sleeve except by an authorized party.

The sliding sleeve type latches 10 and 14, when projected across the respective members or spacing links 9 and the links 13 tend to hold the sections 1-2 and 3-4 of panels A-B as well as end panels C-D in rigid rectilinear position, as shown in Fig. 1. Since the sleeve latches all rotate outwardly, no rough edges are presented as a hazard to the child as it moves about in the bed.

The bottom rails 6-6 of the opposite panels A and B are preferably provided with permanent straps 16 having buckles 17. These buckles are intended to cooperate with a strip of webbing in the nature of a strap 18 which is preferably coated at least on one side, or at intervals, with a non-slipping preparation such, for example, as the type used to prevent rugs from slipping on

floors. Thus, when the strap 18 is applied, as shown in Fig. 1, the non-slipping coating 19 will grip the bed clothing or contacting parts of the bed frame and prevent slipping of the crib on the bed covers.

Assuming that the crib is erected as shown in Fig. 1, it will be understood that the latches 10 and 14 span their respective links to hold the panels A, B, C, D in relatively rectangular relation.

When it is desired to collapse the crib, the sleeves 10 and 14 are rotated to disengage the rods 7 and then slidably moved on their supporting rails 5 and 6. As shown in Fig. 2, for example, the side panel A may be first collapsed inwardly, the section 1 moving toward the end panel C. The sections 3 and 4 of the side panel B may be then moved inwardly toward the spacing link 9 of end panel D. Once this movement has been started, light, effortless pressure to bring end panels C and D together collapse the entire crib, as shown in Fig. 3. The collapsed crib may then be stored in the carton or container S having carrying handles H. The collapsed crib in its carton not only provides convenient means for transportation, but may be readily stored when not in use on the average shelf found in any clothes closet.

When it is desired to erect the crib, it is removed from the carton S and placed upon the bed or other surface. By gripping the top rails 5 of the end panels C and D and pulling them apart, the sections 1-2 and 3-4 of panels A and B tend to assume their erected position. After appropriate adjustment of said sections, the sleeves 10 and 14 may be slidably moved across the links 9 and 13 and then rotated, as previously described, to lock the entire structure in rigid rectangular form. It is then only necessary to coil the strap 18 in the form of a roll and, holding onto one end, roll it beneath the bed until the opposite end becomes available. Both ends of the strap may then be easily and quickly connected with the cam or like type buckles 17, and the crib is ready for use.

From the foregoing it will be apparent that the present invention provides a folding crib attachment entirely devoid of pins, clamps, nuts, bolts, or the like, which are likely to become lost or misplaced or require tools for erection. Moreover, when the crib is erected, it provides a rigid, safe and practical attachment for beds, thereby enabling infants and children to have the advantages of a crib while sleeping on a larger bed surface, and of particular service and advantage while traveling or visiting. Moreover, the present invention makes it unnecessary to have a special bed for children since it is made in such sizes and proportions as to serve a child from infancy to youth, thereby avoiding the necessity and expense of both a crib and a youth bed while, at the same time, training the child to sleep in beds of normal size.

It will, of course, be understood that minor changes in detail and proportions may be resorted to within the scope of the appended claims.

I claim:

1. A collapsible enclosure device erectable to form an oblong rectangular structure, comprising, in combination, opposite rigid unitary end panels of the same width, side panels each including a short section and a long section hingedly connected at their inner ends, the short and long sections being diagonally opposite each other in said side panels, corner hinge means

connecting the outer ends of the short sections with diagonally opposite corners of the end panels, and means for connecting the long sections of the side panels with the other diagonally opposite corners of the end panels; said last named means including, a spacing link connected with each of said long sections and a collapsing hinge whose axis connects the inner end of the link with the related end panel and becomes an extension of the end panel when the structure is erected, and whereby, in collapsing said structure, the inner ends of the short and long sections of the side panels may be manually moved inwardly and directed toward said spacing link to bring all of the connected sections of both side panels and the end panels into parallel relation between said end panels to compactly collapse the entire structure.

2. A collapsible enclosure device erectable to form an oblong rectangular structure, comprising, in combination, opposite rigid unitary end panels of the same width, side panels each including a short section and a long section hingedly connected at their inner ends, the short and long sections being diagonally opposite each other in said side panels, corner hinge means connecting the outer ends of the short sections with diagonally opposite corners of the end panels, and means for connecting the long sections of the side panels with the other diagonally opposite corners of the end panels; said last named means including, a spacing member connected with each of said long sections and a col-

lapsing hinge whose axis connects the inner end of said member with the related end panel and becomes an extension of the end panel when the structure is erected, and whereby, in collapsing said structure, the inner ends of the short and long sections of the side panels may be manually moved inwardly and directed toward said spacing member to bring all of the connected sections of both side panels and the end panels into parallel relation between said end panels to compactly collapse the entire structure.
